197,232

RADIO AND TELEVISION AMPLIFIER ANTENNA

Milton Spirt, 181—25 Midland Parkway,
Jamaica Estates, N.Y.

Filed Mar. 7, 1963, Ser. No. 73,863

Term of patent 14 years

(Cl. D26—14)

Fig. 2.

FIG. 1 is a front elevation of a radio and television amplifier antenna, showing the antenna forming elements in lowered, folded position.

FIG. 2 is a top plan view of the same.

FIG. 3 is a left hand end view of the same.

FIG. 4 is a right hand end view of the same.

FIG. 5 is a rear view of the antenna.

I claim:

The ornamental design for a radio and television amplifier antenna, substantially as shown.
